UNITED STATES PATENT OFFICE.

JOHN J. KNAPP, OF WASHINGTON, DISTRICT OF COLUMBIA.

SAFETY-LOCK FOR BREECH-BLOCKS.

No. 879,652.

Specification of Letters Patent.

Patented Feb. 18, 1908.

Application filed October 16, 1907. Serial No. 397,750.

To all whom it may concern:

Be it known that I, JOHN J. KNAPP, (commander U. S. N.) a citizen of the United States, residing at Washington, in the District of Columbia, have invented certain new and useful Improvements in Safety-Locks for Breech-Blocks; and I do hereby declare the following to be a full, clear, and exact description of the invention, such as will enable others skilled in the art to which it appertains to make and use the same.

This invention relates to means for preventing accidents aboard ship, due to what is known as flare backs, or the escape from the breech of the gun, in an ignited condition, of the gaseous products or other residue remaining in the gun after a discharge. It is well known that horrible accidents occur from these flare backs, and that the cause of the same is not well understood.

Heretofore it has been customary to use in the navy of the United States, a device adapted to force out of the gun all the products of combustion, and other residue left therein after a discharge has taken place, substantially such as is shown in Patent No. 783,050 granted February 21, 1905, jointly to myself and to G. W. Dunn. But at least one accident of the above nature has occurred with a gun which was provided with this device, and it is very probable, if not certain, that the failure of such device to prevent said flare back was due to the fact that no air pressure, or an air pressure too small for the purpose, was in use at the time. That is to say, it is practically certain that either the air compressor was not connected with the air pipes, or else that the pressure in the pipes was not sufficient to clear the gun of all dangerous elements before the breech was opened.

It is the object of my present invention, to provide a means whereby it will be impossible to open the breech of a gun, provided with the device shown in the above patent, unless a sufficient pressure is in the air pipes, to effectually clear the gun of all combustible gases and other products or material, which would be liable to ignite a new charge of powder about to be placed in the gun.

To these ends my invention consists in a means attached to the breech of the gun, co-acting with another means attached to the breech block in such a way as to effectually lock the same, and provided with additional

means adapted to be operated by the air pressure in the pipe, to unlock the breech block, and keep it unlocked whenever there is sufficient pressure in the air pipes to clear the bore of the gun.

My invention further consists in the novel combination of parts more fully hereinafter described and particularly pointed out in the claims.

Referring to the accompanying drawings forming a part of this specification:—Figure 1, represents an elevational rear view of the breech of a gun provided with my improvement. Fig. 2, an elevational side view of my improved lock. Fig. 3, a rear elevational view of my lock on an enlarged scale, and, Fig. 4, a sectional view of the same. Fig. 5, is a sectional view showing the mechanism of the interior structure of the valve.

Like letters refer to like parts in all the views.

A, indicates the breech portion of any type of gun, on which it is desired to place my invention. B, the breech block thereof, and C, the main air pipe adapted to carry air, or water, or both, to the bore of the gun as fully disclosed in the prior patent above mentioned; D, the valve mechanism controlling the admission of air and water into said bore; and E, a connection to one of the nozzles, which conveys the air, or water, or both, to the interior of the gun.

F, indicates a projection connected with the valve mechanism, D, and adapted to be operated by the projection, G, connected to the breech block of the gun when the latter is rotated, and to thereby turn on the air, or water, or both, which is contained in the tube, C, whenever the breech block is unlocked, all as clearly set forth in my former patent above.

On the breech block, B, I fasten in any suitable manner the small lug or projection, H, and provide the same with a slot or cavity adapted to receive the locking bolt or plunger, J, of a spring controlled piston, K, contained in the cylinder, L, provided with the spring, M, which in turn is controlled by the set screw, N. The plunger, J, is provided with a slot, O, near its lower end, and passes through the screw plug, P, in the lower end of the cylinder, L, and is surrounded by the packing ring, Q, provided with the bearing screws, R, and said plunger is also secured to the inverted cup shaped piston, K, by means

of a screw, S, passing through the washer, T, as shown.

The bore of the cylinder, L, is enlarged at its extreme lower end to receive the screw threads for the plug P, and, also, to form a shoulder for the packing ring, Q, through which the said plunger, J, passes air tight. The said cylinder, L, is also preferably screw threaded at its top to receive the closing cap, 10 U, through which the regulating screw, N, passes. Cast integrally with said cylinder, or otherwise securely fastened thereto, is the bracket, V, through which pass the bolts, W, and to one of these bolts is fastened the support, X, carrying the lever, Y, as shown. Said cylinder is also provided with an orifice, A', preferably screw threaded in to which fits one end of the pipe B', the other end of which is connected to the valve mechanism, 15 D, or to the pipe, C, as desired. Said pipe, B', enters the cylinder, L, on that side of the piston, K, opposite to the spring, M, and the fluid entering said cylinder through said pipe tends to force said piston, K, upward against the tension of said spring, M. Whenever the 20 force of said fluid is sufficient to overcome the tension of said spring, M, the plunger, J, is raised out of the slot in the lug, H, and the breech block may be readily unlocked. But whenever the pressure in said pipe is insufficient to overcome the tension of said spring, M, then it is impossible to raise the said plunger, J, except by means of the hand lever, Y. This hand lever is pivoted at C', as shown, in 25 the support, X, and its end, D', enters the slot, O, in the plunger, J. Therefore, by pressing on the other end of said lever, the same may be swung on its pivot and the plunger operated by hand, if desired.

40 The operation of my invention is as follows:—When the gun is fired, the breech block B, is rotated by the usual mechanism, and turns on the fluid in pipe, C, by means of the lug, G, contacting with the projection, E, attached to the valve mechanism, D, in the manner disclosed in my former patent above, and now well known to those skilled in the art. The pressure in the pipe, C, is also, at all times, communicated through the 45 pipe, B', to the piston K, and therefore, keeps that piston raised against the tension of the spring, M, and consequently holds the plunger, J, out of locking contact with the lug, H, on the breech block. Owing to the 50 pressure keeping the said plunger, J, raised at all times, the opening of the breech is not retarded in the least, and the gun may be operated so long as the pressure is sufficient to maintain the plunger, J, out of locking 55 position, precisely the same as if it were not provided with my locking device. But as soon as the pressure in the pipe, C, becomes insufficient to hold the plunger, J, out of locking position, the spring, M, forces the 60 plunger down into contact with the lug, H,

on the breech block, and thereby effectually locks the block, and prevents the breech from being opened.

In practice the spring, M, is so tensioned, by means of the screw, N, that the plunger, J, cannot be lifted by said pressure, unless the said pressure is sufficient to thoroughly clear the gun of all dangerous material when the valve mechanism, D, is operated. In other words, the screw, N, and the spring, M, are so adjusted that should the compressor fail to operate, or should the pipe, C, or any of its connections be shot away or injured, the breech block cannot be unlocked and, therefore, no flare backs could occur. 80 If, however, it is desired to open the breech block, at any time whatever it may be readily unlocked by operating the lever, Y, as above stated.

Of course, I do not limit myself to the precise construction and mode of operation above outlined, for it is evident that the same may be widely varied without departing from the spirit of my invention.

What I claim is:

1. In a gun provided with a breech block, the combination of means to admit fluid under pressure to the bore of said gun, with means adapted to automatically lock said block whenever the pressure of said fluid reaches a predetermined point, substantially as described.

2. In a gun provided with a breech block, the combination of means adapted to admit fluid under pressure to the bore of said gun, means on said block for controlling the flow of said fluid, and means for automatically locking said block, whenever the pressure of said fluid falls to a predetermined point, substantially as described.

3. In a gun provided with a breech block, the combination of means adapted to admit fluid under pressure to the bore of said gun, means on said gun for controlling the flow of said fluid comprising a projection on said block, and a valve device on the breech of said gun with which said projection is adapted to contact, and means on said gun adapted to automatically lock said block whenever the pressure of said fluid falls to a predetermined point, substantially as described.

4. In a gun provided with a breech block, the combination of means to admit fluid under pressure to the bore of said gun, with means adapted to automatically lock said block whenever the pressure of said fluid falls to a predetermined point, said last mentioned means comprising a spring controlled plunger, substantially as described.

5. In a gun provided with a breech block, the combination of means adapted to admit fluid under pressure to the bore of said gun, a lug on said block, a spring controlled plunger adapted to engage said lug, and a connection between said fluid pressure

means, and said plunger, whereby the said block is automatically locked whenever the pressure of said fluid falls to a predetermined point, substantially as described.

6. In a gun provided with a breech block, the combination of a source of fluid pressure, a lug H, secured to said breech block, a plunger J, adapted to engage said lug, a spring M, adapted to control said plunger, 10 means adapted to control the tension of said spring, and a pipe B' connected to said source of fluid pressure, whereby said plunger J, is automatically disengaged from the said lug H, whenever said fluid pressure reaches a 15 predetermined point, substantially as described.

7. In a gun provided with a breech block, the combination of a source of fluid pressure, a valve mechanism D, on the breech of the 20 gun for controlling the same, a lug G, on the said breech block for controlling said valve mechanism, a lug H, also on the breech block, a plunger J, adapted to engage said lug and to lock said block, a cylinder L, in 25 which said plunger reciprocates, and a pipe B' connected to said source of fluid pressure, whereby whenever the said pressure falls to a predetermined point the said plunger automatically locks the breech block, and whenever 30 the said pressure rises to a predetermined point, the said plunger automatically unlocks said block, substantially as described.

8. In a gun provided with a breech block, 35 the combination of a pipe C, containing fluid under pressure, a valve mechanism D, adapted to control said fluid, a lug G, carried by the breech block adapted to control said valve mechanism, a pipe B' connected to said 40 pipe C, a lug H, also carried by said breech

block, a plunger J, adapted to engage said lug H, a cylinder L, with which said pipe B' communicates, and a spring M, controlling said plunger J, substantially as described.

9. In a gun provided with a breech block, 45 the combination of a pipe C, containing fluid under pressure, a valve mechanism D, adapted to control said fluid, a lug G, carried by the breech block adapted to control said valve mechanism, a pipe B' connected to 50 said pipe C, a lug H, also carried by said breech block, a plunger J, adapted to engage said lug H, a cylinder L, with which said pipe B' communicates, a spring M, controlling said plunger J, a set screw M, for regulating 55 the tension of said spring, and means for operating said plunger by hand, when desired, substantially as described.

10. In a gun provided with a breech block, 60 the combination of a pipe C, containing fluid under pressure, a valve mechanism D, adapted to control said fluid, a lug G, carried by the breech block adapted to control said valve mechanism, a pipe B' connected to 65 said pipe C, a lug H, also carried by said breech block, a plunger J, adapted to engage said lug H, a cylinder L, with which said pipe B' communicates, a spring M, controlling said plunger J, a set screw N, for regulating 70 the tension of said spring, and means for operating said plunger by hand, when desired, comprising a support H, and a lever Y, pivoted to said support and engaging said plunger, substantially as described.

In testimony whereof, I affix my signature, in presence of two witnesses.

JOHN J. KNAPP.
